UNITED STATES PATENT OFFICE

FRANK E. WOLCOTT, OF WEST HARTFORD, CONNECTICUT, ASSIGNOR TO THE SILEX COMPANY, A CORPORATION OF CONNECTICUT

DESIGN FOR AN UPPER BOWL COVER FOR COFFEE MAKERS

Application filed January 15, 1932. Serial No. 42,490. Term of patent 14 years.

To all whom it may concern:

Be it known that I, FRANK E. WOLCOTT, a citizen of the United States, residing at West Hartford, in the county of Hartford and State of Connecticut, have invented a certain new, original, and ornamental Design for Upper Bowl Covers for Coffee Makers, of which the following is a specification, reference being had to the accompanying drawing forming part thereof.

In the drawing,—

I claim:—

The ornamental design for an upper bowl cover for coffee makers, substantially as shown and described.

In testimony whereof I affix my signature.
FRANK E. WOLCOTT.
